PORTABLE REFRESHMENT BOOTH

Joseph P. Spang, Quincy, Mass.

Application November 4, 1933, Serial No. 696,653

4 Claims. (Cl. 155—124)

This invention relates to portable booth construction adapted specially for use in installing refreshment booths of the type commonly used in ice cream parlors, restaurants and similar 5 places where refreshment is served.

In my Patent No. 1,928,508, September 26, 1933 I have shown a portable refreshment booth which comprises a partition member having seats hinged thereto and also provided with folding 10 seat-supporting means, the construction being such that a plurality of these partition members with their attached seats may be placed in parallel relation in any room thereby forming a series of alcoves or booths. The present invention has 15 for its object to provide improvements in the construction shown in the above-mentioned patent by which the portable booth is rendered more serviceable for general use.

In order to give an understanding of the invention I have illustrated in the drawings a selected embodiment thereof which will now be described after which the novel features will be pointed out in the appended claims.

Fig. 1 is a perspective view of one of the combined partition and seat units of a portable refreshment booth embodying my invention;

Fig. 2 is a view showing the combined partition and seat unit folded for storage purposes;

Fig. 3 is an end view of a portable refreshment booth embodying my invention with a portion broken out to better show the construction;

Fig. 4 is an edge view of the combined partition and seat unit when it is folded for storage;

Fig. 5 is an enlarged fragmentary view showing 35 the manner in which the seats are hinged to the partition member, the end members nearest the observer being omitted;

Fig. 6 is a section on the line 6—6, Fig. 5 with the end members in position;

Fig. 7 is an enlarged section on the line 7—7, Fig. 3;

Fig. 8 is a section on the line 8—8, Fig. 5 showing the seat folded;

Fig. 9 is an enlarged section on the line 9—9, Fig. 3.

As stated above my invention relates to a portable booth construction which includes a portable unit in the form of a combined partition member and seat member which is designed to be 50 arranged with other units adjacent the wall of a room to provide the desired booths or alcoves.

The combined partition and seat unit embodying my invention is indicated generally at 1. This comprises a partition member 2 which forms the partition between the booths and also the back of the seat, two seat members 3 pivotally connected to the partition member 2 and a pair of seat-supporting end members 4 at each end of the partition member and which provide means for sup-

porting the seats in operative position when the device is in use.

The seat members 3 are pivoted to the lower edge of the partition member 2 so that they may swing downwardly into the plane of the partition member or may be swung upwardly into their horizontal operative position. A simple pivotal connection for the seat members 3 is herein illustrated. It includes a hinge plate 5 secured by screws 6 or otherwise to each end of the partition 65 2 adjacent the bottom thereof, and which is provided with two pintle-receiving openings 7 near its lower edge, and pintles 8 at the ends of the seat members 3 which are received in said openings 7. As herein shown the partition member 2 is at least twice as thick as the seat members 3 so that when the seat members are swung 70 downwardly into the plane of the partition member as shown in Figs. 4 and in dotted lines Fig. 5 the combined thickness of the two seat members 3 is no greater than that of the partition member 2. 75

The seat-supporting members 4 are constructed not only to support the seats 3 in their horizontal operative position but also so as to form ornamental ends or wings to the structure. In 80 the construction shown each end member 4 extends to the top edge of the partition member and is hinged to the end of the partition member through the medium of suitable hinges 9, the latter being constructed to permit each end member to be folded against the partition member when the seats are swung into their vertical position as shown in Fig. 2. 85 90

In the construction shown in Fig. 7 a hinge 95 construction in the nature of a double hinge is employed for each pair of end members 4. This hinge construction comprises a central hinge plate 10 which is secured to the end of the partition member 2 by means of screws 11 or otherwise and which has hinged to each edge thereof a hinge plate 12 which is secured to one of the wings 4 also by means of screws 13. These hinges may if desired be spring hinges, that is, hinges which are provided with a suitable spring 14 that normally tends to swing the end members 4 into their folded position against the partition member as shown in Figs. 2 and 4 and in dotted lines in Fig. 7. With this construction the pivotal axis of each end member is at the vertical corner of the partition member 2, and each end member is shown as extending somewhat beyond its pivotal point as indicated at 15 so that when the two end members are swung outwardly into operative position as shown in Figs. 1, 3 and 7 the edge portions 15 of the two end members of any pair meet each other. These two edge portions also engage the end of the partition member and serve as means to limit the outward 100

swinging movement of the end members. 105 110 115 120

The end members 4, which are also seat-supporting members, are provided with suitable means for supporting the seats 3 when they are in their operative horizontal position. As herein shown each end or seat-supporting member 4 is provided with a seat-supporting rail or cleat 16 on which the end of the seat 3 rests. This rail or cleat is preferably specially constructed so that it not only furnishes a support for the seat but also has an interlocking engagement with the seat which prevents any separating movement of the two seat-supporting members at opposite ends of a seat. The seat-supporting rail 16 is herein illustrated as having a channel shape and as being secured to the seat-supporting member 4 through the medium of screws 17.

Each seat member 3 is provided at its end with a lip 18 which is received in the channel shape of the rail 16 when the seat is in operative position as best seen in Fig. 6. This lip 18 can conveniently be formed by securing an angle iron strip 19 to the under side of each seat at the end thereof, one leg of the angle iron strip forming the lip 18. With this construction each seat-supporting member is tied to the end of the seat which it supports so that there can be no separating movement of the seat-supporting members for any seat sufficient to withdraw the seat-supporting rail or cleat from under the seat.

30. Each unit will preferably be made so that it has a seat on each side of the partition member as shown in Figs. 1 and 3. These units are portable units and can be set up along the wall in any room thereby providing stalls or booths in which tables 24 may be placed for serving refreshments as illustrated in my before-mentioned Patent No. 1,928,508.

If at any time the floor space occupied by the portable booths is desired for other purposes than serving refreshments each unit may be knocked down or folded as shown in Figs. 2 and 4 and then stored in any convenient storage place. The folding of the unit involves raising each seat sufficiently to withdraw the lip 18 from the channel iron supporting rail 16 and then swinging the seats downwardly into the plane of the partition member as shown in Figs. 2 and 4 and in dotted lines in Fig. 5. The end or seat-supporting members may then be folded over onto opposite sides of the partition member thereby reducing the combined partition member and seat to a compact structure occupying little space and which can be easily stored.

55. The structure may be used by simply setting the combined partition and seat units on the floor at the desired locations. If, however, it is desired to anchor these units in place then anchoring screws may be inserted through the openings 20 formed in the feet 21 and screwed into the floor. In order to prevent said feet from splitting I propose to reinforce the upper edge of each foot 21 with a channel iron member 22 which encloses said upper edge and which is provided with an opening 23 in alignment with the screw-receiving opening 20.

I claim:

1. A folding seat and partition unit for portable booth constructions comprising a partition member, a pair of seat-supporting members hinged to each end of the partition member and supporting the latter with its lower edge spaced from the floor, two seat members hinged to the lower edge of the partition member, each seat member hav-

ing a thickness no greater than half that of the partition member and both seat members adapted to swing from a horizontal operative position to a vertical inoperative position beneath and in the plane of the partition member, the seat-supporting members extending above the seats and each member being provided on its inner face with a seat-supporting rail to support the end of the seat, said seat-supporting members being adapted to fold against the opposite sides of the partition member when the seat members are in their inoperative position.

2. A folding seat and partition unit for portable booth constructions comprising a partition member, a seat-supporting member hinged to each end of the partition member, said seat-supporting members supporting the partition member with its lower edge spaced from the floor, a seat member hinged to the lower edge of the partition member and adapted to swing from a horizontal operative position to a vertical inoperative position beneath and in the plane of the partition member, said seat-supporting members extending to the top of the partition member and each having on its inner face a seat-supporting rail on which the end of the seat member rests, said seat-supporting members being foldable against the partition member when the seat is in its inoperative position.

3. A folding seat and partition unit for portable booth constructions comprising a partition member, a pair of seat-supporting members hinged to each end of the partition member and supporting the latter with its lower edge spaced from the floor, two seat members hinged to the lower edge of the partition member, each seat member having a thickness no greater than half that of the partition member and both seat members adapted to swing from a horizontal operative position to a vertical inoperative position beneath and in the plane of the partition member, the seat-supporting members extending above the seats, and a channel-shaped seat support secured to each seat-supporting member on its inner face and on which the seat-supporting member rests, each seat having a lip to be received in the channel of the seat support.

4. A folding seat and partition unit for portable booth constructions comprising a partition member, a hinged plate secured to each end thereof at its lower edge, said plates projecting below said lower edge, a pair of seat-supporting members hinged to each end of the partition member and supporting the latter with its lower edge spaced from the floor, said partition members extending above the hinge plates, two seat members having pintles journaled in said hinge plates, each seat member having a thickness no greater than half the thickness of the partition member, whereby the seat members may swing from a horizontal operative position into a vertical inoperative position beneath and in the plane of the partition member, a channel-shaped seat support secured to the inner face of each seat-supporting member and on which the end of the seat may rest, each seat having a depending lip to be received in the channel of the seat support when the seat is in operative position, said seat supports being foldable against opposite sides of the partition member when the seats are in inoperative position.
